UNITED STATES PATENT OFFICE.

DANIEL J. MURNANE, OF ST. LOUIS, MISSOURI.

VENTILATED WINDOW-FRAME.

967,955.

Specification of Letters Patent. Patented Aug. 23, 1910.

Application filed May 5, 1909. Serial No. 494,183.

To all whom it may concern:

Be it known that I, DANIEL J. MURNANE, a citizen of the United States, residing at St. Louis, Missouri, have invented a certain 5 new and useful Improvement in Ventilated Window-Frames, of which the following is a full, clear, and exact description, such as will enable others skilled in the art to which it appertains to make and use the same.

10 This invention relates to window frames, and particularly to that type which are provided with ventilating openings.

The main object of my present invention is to provide a window frame of the type referred to which is so constructed that the 15 ventilating openings cannot be seen from the outside of the window.

Another object is to provide a ventilated window frame in which the ventilating 20 openings are arranged in such a manner that water or moisture cannot pass through same into the interior of the window. And still another object of my invention is to provide a ventilated window frame that presents a 25 neat and ornamental appearance.

Figure 1 of the drawings is a front elevational view of a wooden window frame constructed in accordance with my invention; Fig. 2 is an enlarged cross sectional view 30 taken on the line 2—2 of Fig. 1; and Fig. 3 is a cross sectional view illustrating my invention embodied in a metallic window frame.

Referring to Fig. 1 of the drawings, 1 designates the front face of the wall of a building, and 2 designates a wooden window frame that is set into said wall, said frame being used for supporting a plate of glass 3 that is retained in position by means of 35 outside clamping pieces 4 that are connected to the frame 2 in any suitable manner. The top, bottom and side pieces of the frame 2 are provided with ventilating openings 5 which extend from the inside of the frame to 40 the outside thereof so that air can pass through same and thus ventilate the room or compartment which the window closes. The outer edge of the frame 2 is provided with a rabbet or groove 6 that extends completely 45 around same so as to form a channel between the frame and the wall 1 in which it is arranged, and the outside clamping pieces 4 which retain the plate of glass in position are so arranged that they will not completely cover this channel. The outer ends

of the ventilating openings 5 terminate at this channel or groove 6 so that the ends of said ventilating openings cannot be seen from outside the window but still the air can pass through same, as indicated by the arrows in Fig. 2.

A window frame of the construction above described permits enough air to enter the compartment which the window closes so as to thoroughly ventilate said compartment but the ventilating openings cannot be seen from the outside of the window because they terminate at the side wall of the groove or rabbet 6 which is formed in the outer edge of the frame. In the illustration herein shown, the channel or groove 6 between the frame 2 and the wall 1 is proportionately larger than is used in actual practice so as to more clearly set forth my invention. Still another desirable feature of a window 70 frame of this construction is that water or moisture cannot pass through the ventilating openings 5 as said openings are inclined downwardly from the interior to the exterior of the frame 2, as shown in Figs. 1 75 and 2.

In Fig. 3 I have illustrated a metallic window frame constructed in accordance with my invention, said frame being composed of metallic outside clamping pieces 7 and inside 80 clamping pieces 8 between which the plate of glass is arranged. The wall 9 in which the window opening is formed, has an approximately L-shaped metallic member 10 connected thereto so as to form the bottom 90 and rear wall of a ventilating chamber whose top and front walls are formed by the clamping members 8 and 7, respectively, the inside clamping member 8 being carried by a number of supports 11 on which the 95 lower edge of the plate of glass rests. These supports 11 are arranged inside of the ventilating chamber and are spaced away from each other so as to not interfere with the passage of the air into and out of the ventilating chamber. The lower edge of the outside clamping piece 7 terminates a short distance above the horizontal leg of the L-shaped metallic member 10 so as to form a narrow slot 12 that permits the air to pass 100 into the ventilating chamber, as shown by the arrows in Fig. 2, and thus escape therefrom through the slot 13 formed between the edge of the inside clamping piece 8 and the vertical leg of the L-shaped metallic 110

member 10, thus thoroughly ventilating the room or compartment which the window closes.

The main advantage of a construction of the character just described is that no ventilating openings can be seen from outside of the window, the slot 12 which admits the air being so narrow that it is not noticeable. In view of the fact that this slot 12 is continuous it is not as liable to become clogged with dirt as the constructions of this character that have heretofore been in use which were provided with a number of spaced holes or openings for admitting air into the window.

While I have herein shown an L-shaped member 10 and clamping pieces 7 and 8 arranged at only the lower edge of the plate of glass, it will, of course, be understood that this same construction could extend all around the window and therefore I do not wish it to be understood that my broad idea is limited to a construction in which a ventilating chamber is arranged at only the lower edge of the plate of glass. I have not herein shown any means for retaining the outside clamping piece 7 in position for it is immaterial so far as my present invention is concerned how said clamping piece is held in position. I also wish it to be understood that my broad idea is not limited to the exact construction shown in Figs. 1 and 2 for, if desired, the groove or channel 6 which extends around the frame could be formed by using an outside clamping piece 4 of less width than the frame proper in which the glass is mounted, the channel 6

in such a construction consisting of the space between the outer edge of the outside clamping member 4 and the wall of the building.

Having thus described my invention, what I claim as new and desire to secure by Letters Patent is:

1. A window frame provided with ventilating openings that extend from the interior to the exterior of said frame, the outer ends of said openings terminating at one wall of a groove or channel which is formed in the outer edge of the frame. 45

2. A window frame having ventilating openings that extend from the interior to the exterior thereof, and a channel formed between the frame and the wall or member in which it is arranged, the outer ends of said ventilating openings terminating at one wall of said channel in such a manner that they cannot be seen from outside the window. 50

3. A window frame provided in its outer edge with a groove or rabbet that forms a channel between the frame and the wall or member in which it is mounted, and ventilating openings in said frame that incline downwardly from the interior of said frame and terminate at one wall of said channel in such manner that they cannot be seen 55 from outside the window. 60

In testimony whereof I hereunto affix my signature in the presence of two witnesses, this first day of May 1909.

DANIEL J. MURNANE.
